United States Patent Office

Des. 188,234
Patented June 14, 1960

188,234

FOOD CUTTER

Orloff W. Holden, 9101 S. Longwood, Chicago, Ill.

Filed July 24, 1959, Ser. No. 56,921

Term of patent 14 years

(Cl. D89—1)

I claim:

The ornamental design for a food cutter, as shown.
